TIME STAMP

Clair D. Lake, Binghamton, N. Y., assignor to International Business Machines Corporation, New York, N. Y., a corporation of New York

Application October 28, 1933, Serial No. 695,647

14 Claims. (Cl. 101—287)

This invention relates to time stamps in general and, more particularly, to time stamps which are operated, and/or controlled by electricity.

5 The broad object of the invention is to generally improve time stamps by providing operating and controlling mechanisms which enable a more uniform impression to be had and whose operation is more reliable.

10 A general object is to provide novel controlling and operating means for electrically controlled time stamps which means are more or less independent of transient phenomena or periodically changing conditions of the supply line

15 such as variations in potential. For example, when alternating current must be used to operate the clamp the novel means is adapted to be more or less independent of the point in the alternating current wave at which the circuit is closed to bring about an operation of the stamp.

20 A specific object is to provide an operating mechanism for time stamps which includes a spring-operated toggle as the means for operating the impression taking device.

25 Another specific object is to provide an operating mechanism for time stamps which is released for operation by means of a relatively low power electromagnet or solenoid.

30 A further specific object is to provide a time stamp operating means which is operated by a relatively light spring and restored by a solenoid or electromagnet, the control of the solenoid or magnet being of an interlocking nature such as to insure that the operating means is fully restored before a second operation can take place.

35 Another specific object is to provide a time stamp operating mechanism which is spring-operated and controlled by two interlocked sole-noids or electromagnets in such fashion as to make said mechanism absolutely reliable in its action and more or less independent of variations in potential of the current supply line.

40 A further specific object is to provide controlling mechanism for time stamps which is adapted to be controlled by either the insertion of the paper to be stamped or by the pressure of the operator's fingers.

45 Still another specific object is to provide a time stamp controlling mechanism in which provision is made for preventing unwanted repeated impressions.

50 Various other objects, advantages, and features of the present invention will be specifically 55 pointed out in the following description and

claims or will be apparent from a study of the description, claims and the accompanying drawings:

In the drawings:

Fig. 1 is a vertical longitudinal section through 5 a time stamp embodying the present invention;

Fig. 2 is a vertical transverse section on the line 2—2 in Fig. 1;

Figs. 3, 4, and 5 are similar views taken on the lines 3—3, 4—4, and 5—5, respectively, in 10 Fig. 1;

Fig. 6 is a detail view of certain parts in Fig. 1;

Fig. 7 is a view showing a modification;

Fig. 8 is a circuit diagram.

The time stamp is of the same general type as the one described in Patent No. 1,798,583 granted May 20, 1930 to L. C. Bishop and A. L. Sprecker. The entire time stamp is mounted upon a base casting 10 which has lugs 11 supporting a frame casting 12. This frame casting supports, at its right-hand end (Fig. 1), a printing head which may be similar to the one described in the above patent. The frame 12 is enclosed by the lower half 13 of a two part housing or casing, the upper half 14 of which encloses the printing head. The latter has not been shown as the present invention relates to means for operating and controlling the impression taking means or platen.

The printing wheels have been generally indicated in Fig. 1 by a broken line circle 16. The frame 12, the side frames (not shown) supporting the printing head, and the two-part housing 13, 14, are so disposed as to provide a deep 35 unobstructed opening 17 to receive the papers to be stamped.

The impression taking means may consist of a platen 18 of resilient material mounted on a plate 19 which is recessed to receive the platen 40 as shown in Fig. 3. The frame 12 beneath the printing wheels 16 is provided with a rectangular opening 20 in which the platen 18 and its supporting plate 19 are free to move vertically to project a paper resting on the platen against 45 the printing wheels 16 in the usual manner. The plate 19 is adjustably secured, as by screws 21, 22, to a frame 23 (Figs. 1 and 3) shaped like an inverted U and composed of sheet metal, the plate 19 being secured to the upper horizontal 50 part of the frame. The side members of the frame 23 are slotted as at 24 to embrace studs 25 each riveted to the inside of one of the vertical members of a U-shaped sheet metal sub-frame 26 secured to the base 10 as by screws 27. 55

Tie bolts 28 and spacing bushings 29, connecting the upper ends of the frame 26, have the double purpose of guiding the frame 23 in its vertical movements and rigidly securing the upper ends of frame 26 in spaced relationship.

Adjacent each vertical member of frame 23 is a toggle comprising a pair of links 30, 31 the upper ends of links 30 being pivoted to the frame 23 as at 32 and the lower ends of links 31 being pivoted to the studs 25. The pairs of links 30, 31 are pivotally joined together by a short shaft 33 which passes through a bushing 34 holding the two pairs of links in spaced relationship as shown in Fig. 1. It is fairly obvious that straightening of the two toggles comprising the links 30, 31 will ultimately result in the platen being moved upwardly toward the printing wheels 16.

The straightening of the toggles is effected by means of a spring 35 anchored to a stud 36 carried by the frame 12 and to a stud 37 secured to a member 38 rigidly mounted on a shaft 39 journalled in frame 26. The member 38 is slotted to embrace an enlargement of the bushing 34, the slot being wide enough to allow a certain amount of looseness or lost motion between member 38 and the enlargement of bushing 34, as shown in Fig. 3. The member 38 has a downwardly projecting arm 40 to which is pivoted one link 41 of a toggle comprising links 41, 42. The link 42 is pivoted at its left-hand end (Fig. 3) to link 41 and at its right-hand end to a bracket 43 secured to frame 26. When the parts are in the position of Fig. 3, a bent-over lug 44 formed in link 42, is engaged by a shoulder in a latch arm 45 secured to a short shaft 46 which is journalled in frame 26. Fig. 3 shows the normal position of the parts in which the toggles comprising links 30, 31, are fully bent so that the frame 23 is freely resting on studs 25, and platen 18 is flush with the edges of opening 20, permitting a paper to be freely inserted in the opening 17 in readiness for the stamping operation. In this position of frame 23, the spring 35 tends to rock member 38 in a counterclockwise direction to bend the partially bent toggle comprising links 41, 42 but such action is prevented by latch arm 45.

The latch arm 45 is operated by means of a solenoid 47 (Fig. 2) carried by a frame 48 which is secured to the base 10 in front of frame 26. The plunger 49 of solenoid 47 is pivoted at 50 to an arm 51 secured to a short shaft 52 journalled in frame 26. Rearwardly of the frame 26 (Fig. 3) the shaft 52 has secured thereto an arm 53 which is connected by a link 54 to an arm 55 secured to the shaft 46 carrying the latch arm 45. It is plain that energization of solenoid 47 will rock arm 51 and shafts 52, 46 in a clockwise direction through the connections 53, 54, 55, thus disengaging the shoulder in latch arm 45 from bent-over lug 44.

The member 38 will now be free to rock in a counterclockwise direction under the influence of spring 35 thus forcing shaft 33 to the left, after a slight preliminary movement to take up the lost motion, (Fig. 3) straightening the toggles 30, 31 and forcing the platen 18 upwardly toward type wheels 16.

The parts are restored to the position of Fig. 3 by means of a solenoid 56 (Figs. 1 and 4) mounted to the right of the frame 26 (Fig. 1). The solenoid 56 comprises an inverted U-shaped frame 57 of magnetic material secured to a relatively thick rectangular block 58 also of mag-

netic material and rigidly mounted on lugs 59 formed in the base 10. The block 58 is provided with a circular opening 60 which acts as a guide for the plunger 61 of the solenoid, which plunger normally rests on a resilient cushion 62 secured to the base 10 as shown in Fig. 4. Both the plunger 61 and the block 58 have slots or recesses 63 and 64, which coact to form a relatively long recess. The shaft 39 extends rearwardly through a hole in block 58 (Fig. 3) and 10 the recess 64 where an arm 65 is secured to said shaft as shown in Fig. 4. The arm 65 extends into the recess 63 and is adapted to be engaged by a short pin 66 carried by plunger 61.

When the spring 35 is effective to straighten 15 the toggles 30, 31 and move the platen upwardly, the shaft 39 will rock counterclockwise (Fig. 4) and arm 65 will move to the position shown by broken lines in Fig. 4 thus preventing further movement of the member 38. This will occur 20 just before the platen forces the paper to be stamped against the printing wheels 16 but the looseness of the slot in member 38 will permit the momentum of the platen to convey the latter further upwardly a slight amount thus causing 25 the impression to be made by a sharp blow of the platen rather than by a steady pressure of relatively longer duration. This mode of operation also prevents wedging the paper to be stamped in case the platen is not retracted properly, as, after such a blow, the platen and frame 23 will fall an amount sufficient to again take up 30 the slack in the connection to member 38 thus releasing the paper in readiness for removal.

After each printing operation the solenoid 35 35 is energized in a manner hereinafter to be described, causing plunger 61 to move upwardly, rocking shaft 39 in a clockwise direction due to the coaction between pin 66 and arm 65, thus drawing toggle 41, 42 back to the slightly bent 40 position of Fig. 3 where the shoulder in latch arm 45 will reengage lug 44, being drawn to that position by the action of a spring 67 anchored to arm 53 and to a stud carried by frame 26 (Fig. 3).

The construction just described has a number of important features of improvement. One of these features is the use of toggles which permits using a spring for operating the platen, the operating force of which spring may be very weak in comparison to the force required to operate the platen by direct action. It is quite obvious from Fig. 3 that a small force applied to the common pivots of the toggles 30, 31 in a direction transverse to the line of action of the platen 18 produces a much greater force on the line of action of the platen. This force becomes greater as the toggles are straightened out and, as the movement produced by spring 35 is extremely rapid, it is plain that the relatively weak spring produces quite a large force of impact of the platen against the type wheels. This feature is especially important in time stamps of the type described in the above patent as, in addition to the six of more type wheels necessary to 50 print the time, day of month, year, and so on, there may be numbering wheels, electrotypes, and the like, so that the surface of the platen may amount to several square inches in area and require a considerable force to operate it. In 55 former time stamps, like that of the above patent, the impact of the platen was caused by direct action of a magnet or solenoid which necessarily had to be very large and heavy and, in spite of the size of the operating magnet or 60

solenoid, the impression of the type was not always even and sharp.

Another feature is that the operation of the time stamp is more reliable when alternating current must be used to operate the time stamp, since the impact of the platen is always uniform, being due to spring action rather than subject to the uncertain action of the alternating current which is notoriously unreliable for operation of magnets and solenoids.

As an example, if, as sometimes happens in former machines, the contacts controlling the operation of the solenoid or magnet producing the impact of the platen came after the peak point of the alternating current wave, the force of impact would be sluggish and weaker than if closure occurred at or slightly prior to the peak point. This is undesirable since it is important that the initial movement of the platen be as rapid as possible in order to gain sufficient momentum in the short distance the platen travels under the direct action of the magnet or solenoid to ensure completion of the stroke by the momentum permitted by the usual lost motion of the parts connecting the platen and its operating solenoid or magnet. With the present construction the main solenoid 56 merely restores the platen, and the solenoid 47, being small and having no heavy work to perform can operate very quickly. Obviously, only a very small force is required to keep the toggle 41, 42 in the nearly straight position of Fig. 3 and hence the pressure on latch 45 is very small permitting the use of a small quick acting solenoid to release the latch. Indeed, as constructed, a very light pressure of a finger on the end of plunger 49 is amply sufficient to release the latch arm 45, nevertheless, the operation of the platen is extremely rapid and a clear, uniform impression is always obtained irrespective of the point in the alternating current wave at which solenoid 47 is energized.

As will now be explained in detail, the control of the main solenoid 56 is of an interlocking nature such that current sufficient to fully restore the platen is always obtained. Since the only requirement for successful operation is the restoration of the platen as quickly as possible, it is unimportant if the solenoid 56 does not initially move the platen at a high rate of speed provided sufficient current passes through the solenoid to fully restore the platen.

The energization of the solenoid 47 may be effected by pressure of a finger on a button 68 (Fig. 1) secured to a short plunger 69 slidably mounted in a guide bushing 70 carried by the upper half 14 of the housing.

The right-hand or rear end (Fig. 1) of plunger 69 is in position to engage a bent over lug 71 formed in a link 72 whose left end in said figure is slidably mounted upon a slot in a bracket 73 secured to the frame carrying the printing wheels 16. A leaf spring catch 74 secured to bracket 73, normally overhangs and holds the link 72 in the slot in the bracket 73 but permits removal of the link when making repairs, replacements, or adjustments. The right-hand end of link 72 is pivoted at 75 to a vertically extending lever 76 pivoted at 77 to the frame 57 of solenoid 56. Normally a spring 78, anchored to a pin 79 on frame 57 and to a flange 80 formed in lever 76, holds the parts in the position of Fig. 1 with a lug 81 offset from link 72 abutting bracket 73. The flange 80 is slotted

to support a link 82 which is pivoted at 83 to a rectangular block 85.

The block 85 is pivotally mounted on a rod 86 journalled in a bracket 87 secured to the frame 12. A T-shaped contact member 88 is mounted on and insulated from the block 85 and extends downwardly between a front pair of contacts 89 (Fig. 5) and a rear pair of contacts 90 (Fig. 1) mounted on opposite sides of a rectangular block 91 of insulating material secured to the base 10. The construction is such that the T-shaped contact member 88 bridges contacts 89 in the position of Fig. 1 and bridges contacts 90 when block 85 is moved a slight amount counterclockwise. Normally a spring 92 anchored to link 82 and to the flange 80 in lever 76, holds the block 85 and link 82 in the position of Fig. 1 with contact member 88 bridging contacts 89. In this position of the parts, a lug 93 formed in link 82 is slightly to the right (Fig. 1) of the flange 80. When button 68 is pressed to the right (Fig. 1) by the operator, the link 72 will be likewise moved to the right rocking lever 76 clockwise. The flange 80 will then engage the lug 93 and force link 82 to the right thereby rocking block 85 and contact member 88 in a counterclockwise direction to bridge contacts 90. As will be seen in Fig. 8, this operation energizes the solenoid 47 and the printing operation takes place as described above.

35 Energization of solenoid 56 to cause the restoration of the platen 18 to normal position is accomplished by the upward movement of platen 18. Pivoted at 94 to the frame supporting printing wheels 16 is a lever 95 having at its front or right-hand end (Fig. 1) an offset lug 96 in the path of movement of the platen. The lever 95 is bent to a U-shape at its rear end, in order to avoid striking parts of the frame and certain mechanism not shown, and is connected by a vertical link 97 to an arm 98 of a bracket secured to the front face of a block 99 pivotally mounted on rod 86 (see Figs. 5 and 6 also). The block 99 may be exactly like the block 85 if desired, and like the latter, may have secured thereto a T-shaped contact member 100 coacting with a pair of contacts 101 like contacts 90. A spring 102 anchored to the base 10 and to a bracket secured to block 99, as by one of the screws receiving member 100 to the said block, normally holds the parts in the positions of Figs. 1 and 6 wherein the contacts 101 are not bridged. A slotted plate 103 is also secured to block 99 as by the same screws which secure bracket 98 to said block (Fig. 5), and into the slot in said plate extends a latch 104 pivotally connected to the frame 57 on the left-hand side thereof (Fig. 4), the latch being suitably bent to permit such connection. The latch 104 is urged downwardly by a spring 105 and normally rests at the bottom of the slot in plate 103 with a latching shoulder 106 formed in the latch occupying a position slightly rearwardly or to the left (Fig. 6) of the plate 103.

65 The shaft 39 is extended to the rear of the solenoid 56 beneath the latch 104 and has secured thereto an arm 107 having a pin and slot connection to a link 108 pivoted to arm 98 at the point where link 97 is pivoted. When the parts are in the normal position of Fig. 5, movement of the member 100 to bridge contacts 101 is positively prevented by the pressure of the pin or arm 107 at the upper end of the slot in link 108. The arm 107 has a bent-over lug 109

in the plane of a rock lever 110 loosely pivoted on shaft 39. The left-hand end of this rock lever has secured thereto a block 111 extending upwardly beneath the latch 104.

5 The other arm of the lever 110 extends to the right beneath the link 82. Normally a spring 112 holds the rock lever in the position of Fig. 5 where it rests on lug 109.

When the button 68 is pressed to energize 10 solenoid 47, the latter will cause the platen 18 to be operated as described. The shaft 39 will be rocked in a counterclockwise direction (Fig. 5) as the platen moves upwardly and the rock lever 110 will follow due to the effect of spring 15 112. The right-hand end of lever 110 will then lift the link 82 enough to disengage lug 93 from the flange 80 whereupon spring 92 (Fig. 1) will draw the link 82 to the left. As a consequence of this movement of link 82, contacts 89 will 20 again be bridged by contact number 88 and the circuit through contacts 90 will be broken.

During the counterclockwise movement of lever 110 the pin on arm 107 will move downwardly in the slot in link 108 and the block 111 25 will also move downwardly to permit latch 104 to drop at the proper time. Near the end of the upward movement of the platen the latter will engage the lug 96 (Fig. 1) and rock lever 95 in a clockwise direction thus moving link 97 downwardly and rocking arm 98 and block counter-clockwise (Fig. 6) causing bridging of contacts 101 by number 100. The plate 103 will move 30 with block 99 with the result that the shoulder 106 in latch 104 will get in front of said plate 35 and permit latch 104 to drop slightly thus holding the block 99 and member 100 in shifted position with contacts 101 bridged by said member.

Since contacts 89 have also been caused to reclose by the initial movement of lever 110, at the 40 end of the upward stroke of the platen the solenoid 56 will be energized and will effect restoration of the platen and its operating mechanism to starting position as described. During the restoration of the platen, shaft 39 will be 45 rocked in a clockwise direction causing similar movement of lever 110 allowing link 82 to drop to the position of Fig. 1.

During the last part of the return movement 50 of lever 110, the block 111 will strike latch 104 and raise it sufficiently to disengage shoulder 106 from plate 103 and permit block 99, plate 103, and member 100 to return to the position of Fig. 6, under the influence of spring 102, thus interrupting the circuit through contacts 101.

Link 108 prevents the member 100 from bridging 55 contacts 101 when the platen 18 is in its normal position and also operates to positively move member 100 to the position of Fig. 6, thus counteracting possible sticking of the contacts or failure of the spring 102 to return the parts to normal position. The lifting of link 82 prevents a second operation of the time stamp unless the button 68 is released as the contacts 90 can not be again bridged by member 88 until the button 65 68 has been released to permit link 82 and lever 76 to resume their normal positions with lug 93 in the rear of flange 80.

Fig. 7 illustrates a modification wherein the 70 operation of the time stamp is directly initiated by the paper to be stamped. The lever 76 is replaced by a short lever 76a which is shaped very much like the lower half of lever 76, having a flange 80a like the flange 80, and is pivoted at 71a. A spring 72a holds the lever in the position 75 of Fig. 7 wherein the upper end of lever 76a

abuts the forward end of a suitable slot cut in frame 12 and also projects into the opening 17. When the paper to be stamped is pushed into the opening 17, the rear edge of said paper will strike the upper end of lever 76a and rock it clockwise a distance sufficient to cause member 88 to bridge contacts 90 through the action of link 82 as previously described. It is preferable that in this case the springs connected to link 82 and lever 76a be as light as possible to prevent the papers inserted in opening 17 from buckling against lever 76a without operating the latch.

While there has been shown and described and pointed out the fundamental novel features of the invention as applied to a single modification, it will be understood that various omissions and substitutions and changes in the form and details of the device illustrated in its operation may be made by those skilled in the art without departing from the spirit of the invention. It is the intention therefore to be limited only as indicated by the scope of the following claims.

What is claimed is as follows:

1. In a time stamp, an impression element, 25 toggle means connected to said element and adapted when straightened to operate said element to take an impression, a spring having a tendency to straighten the toggle means, means normally holding the toggle means in bent position, and a device for releasing the last named means to permit the spring to straighten the toggle and operate the impression element. 30

2. In a time stamp, an impression member, 35 a pair of toggles connected to the impression member and adapted to be straightened to operate the impression member to take an impression, a member for straightening the toggles, a spring for operating said member, a latch for restraining said member and its spring against 40 operation, and an electromechanical device for releasing the latch to permit an operation of said member.

3. In a time stamp, an impression element, a 45 toggle connected to the impression element and adapted to be straightened to operate the impression element, a member having a lost motion connection to the first named toggle for straightening the latter, a spring connected to said member and normally tending to operate the later to straighten the first named toggle, a second toggle connected to said member and adapted when partially bent to prevent said member from straightening the first toggle, means for holding the second toggle in partially bent position, and an electromechanical device for releasing the last named means whereby to permit the second toggle to bend a further extent. 55

4. In a time stamp, an impression element, a 60 light spring, means adapted to be operated by the light spring for operating the impression taking element; and releasable means for restraining the spring against operation including a partially bent toggle and a latch holding the 65 toggle in partially bent position.

5. In a time stamp, an impression element, 70 toggle means connected to said element and adapted when straightened to operate said element to take an impression, a spring having a tendency to straighten the toggle means, means normally holding the toggle means in bent position, a device for releasing the last named means to permit the spring to bend the toggle and operate the impression element, an electro- 75

mechanical device for bending the toggle means to restore the impression element, and means operated by the impression element for initiating operation of the electromechanical means after 5 an impression has been taken.

6. In a time stamp, an impression member, a pair of toggles connected to the impression member and adapted to be straightened to operate the impression member to take an impression, a member for straightening the toggles, a spring for operating said member, a latch for restraining said member and its spring against operation, an electromechanical device for releasing the latch to permit an operation of said 10 member, means for restoring and relatching said member, and means connected to said member for preventing a second operation of the electromechanical device before said member has been relatched.

15 7. In a time stamp, an impression element, toggle means connected to said element and adapted when straightened to operate said element to take an impression, a spring having a tendency to straighten the toggle means, means 20 normally holding the toggle means in bent position, a device for releasing the last named means to permit the spring to straighten the toggle and operate the impression element, means for bending the toggle to restore the latter to normal bent position, and means connected to said toggle for preventing a second operation of said device before the toggle is fully restored to bent position.

25 8. In a time stamp, an impression element, a light spring, means adapted to be operated by the light spring for operating the impression taking element, releasable means for restraining the spring against operation including a partially bent toggle and a latch holding the 30 toggle in partially bent position, a low power solenoid for operating said latch to release the toggle, a relatively higher power solenoid for restoring the impression element against the tension of said spring, and means connected to 35 the toggle for preventing a second operation of the first named solenoid before the second named solenoid has fully restored the impression element.

40 9. In a time stamp, an impression element, a light spring, means adapted to be operated by the light spring for operating the impression taking element; releasable means for restraining the spring against operation including a partially bent toggle and a latch holding the toggle 45 in partially bent position, a solenoid for operating said latch to release the toggle, a circuit for controlling said solenoid, a second solenoid for restoring the toggle to latching position, means controlled by the impression element for energizing the second solenoid, and means in said circuit and controlled by movement of the toggle for preventing a second operation of the first solenoid before the second solenoid has restored 50 the toggle to latching position.

55 10. In a time stamp, an impression element, toggle means connected to said element and adapted to be straightened to operate the impression element to take an impression, means tending to straighten the toggle means, means

5 preventing straightening of the toggle means, an electromechanical device for operating the preventing means to release said toggle for an operation, means for bending the toggle to restore the latter and impression element to normal position, an electric circuit for controlling said device, and means in said circuit controlled by movement of the toggle for preventing a second operation of the electromechanical device before the toggle and impression element are 10 fully restored.

15 11. In a time stamp, an impression element, a light spring, means adapted to be operated by the light spring for operating the impression taking element; releasable means for restraining the spring against operation including a partially bent toggle and a latch holding the toggle in partially bent position, a solenoid for operating the retaining means to release the operating means, a circuit for controlling said solenoid, contacts in said circuit, means for operating said contacts to close the circuit and adapted to be disconnected from said contacts to permit the latter to reopen, means for restoring the impression element and its operating means, and means operated by the impression element for disconnecting the contact operating means.

20 12. In a time stamp, a printing element, an impression element coacting therewith, toggle mechanism connected to the impression element, means normally tending to straighten the toggle and mechanism and thereby operate the impression means to take an impression from the printing element, means for holding the toggle mechanism in bent position, and a trip device for releasing the holding means, said device being actuated by a paper to be stamped when placed in position between the impression element and printing element.

25 13. In a time stamp, a printing element, an impression element co-operating therewith, a toggle device connected to the impression means and adapted when straightened to move the impression element toward the printing element 45 to take an impression, means normally tending to straighten the toggle, releasable means normally holding the toggle device in bent position, means for releasing the holding means, and a normally ineffective retracting device for the toggle device automatically rendered effective by movement of the impression element during its impression taking stroke.

30 14. In a time stamp, a printing element, an impression element co-operating therewith, a toggle device connected to the impression means and adapted when straightened to move the impression element toward the printing element to take an impression, means normally tending to straighten the toggle, releasable means normally holding the toggle device in bent position, means for releasing the holding means, a normally ineffective retracting device for the toggle device automatically rendered effective 55 by movement of the impression element during its impression taking stroke, and means for preventing a second operation of the releasable means before the toggle device is fully retracted.
